MACHINE FOR PRODUCING CAMS

Robert Musyl, Vienna, Austria

Application January 21, 1949, Serial No. 72,044
In Austria January 24, 1948

8 Claims. (Cl. 51—101)

1

The object of the invention is a process and a device or a machine-tool for the precise production of non-circular profiles, and in particular of cams on cam-shafts, or the like, which in many respects presents great advantages over the hitherto known processes and devices.

Hitherto the cams on the cam-shafts have been produced by means of grinding machines, operating according to the copying or duplicating process, which entails the necessity of using a master-cam of a shape identical to that of the finished cam to be produced, and of employing a copying device for making the shape of said master-cam bear upon the motion of the workpiece, as this is also customary with other copying processes. The disadvantage of that process, however, resides in even a slight wear of the tool, i. e. of the grinding wheel in case of grinding machines, entailing a modification of the cam shape which has a highly detrimental effect on the operations of control and distribution for which the defective cam may be used. If an irregular cam-shaft of this kind is e. g. employed in an internal combustion engine the diagram (or chart) of the control and distribution operation is distorted, resulting in a reduction of the engine efficiency.

It has been found that the motion of the masses in the pure copying process, in which the work-piece executes a swinging or oscillating motion together with the headstock and the tailstock, impedes an amelioration of the process. Hence, it is one of the main features of the present invention to have the workpiece execute a rotary motion about a stationary axis, whereas to the tool not only the rotary motion is imparted required for grinding, but also a swinging or oscillating motion indispensable for giving the work-piece the outer shape desired.

According to the invention the tool contacts the workpiece continually in the perpendicular to the curve at the time being, whereby with rotary tools said perpendicular to the curve passes through the center of the tool.

Further and other objects of the present invention will be hereinafter set forth in the accompanying specification and claims, and are shown in the drawings which, by way of illustration, show what I now consider to be preferred embodiments of the invention.

In the drawings:

Figures 1 to 4 diagrammatically illustrate the relative position of the work and of the grinding disc at various operating phases;

Figure 5 is a diagram showing the path of the

2

grinding wheel relative to the flank of the work which is ground;

Figure 6 is a diagrammatic side view of a mechanism for moving the grinding wheel relatively to the work according to the invention;

Figure 7 is a front elevation of a machine according to the invention;

Figure 8 is a top view of the machine shown in Figure 7;

Figure 9 is a part-sectional view of the machine according to Figures 7 and 8 and taken transversely to the axes of rotation of the work, of the grinding disc, and of the shaft of the motor driving the disc;

Figure 10 is a plan view of a machine for simultaneously grinding four cams, according to the invention.

The Figs. 1-4 show four different positions of the grinding wheel relatively to the workpiece to be machined i. e. in this particular case the cam to be produced. In Fig. 1 the main axis *a* of the cam coincides with the diameter *b* of the grinding wheel *c*, i. e. the two centers *d* and *e* of the cam and the grinding wheel are located in the same horizontal line (i. e. the same level). The perpendicular to the curve, composed of the two axes *a* and *b*, passes through the centers *d* and *e*. When the cam moves anticlockwise, the center *e* of the grinding wheel is horizontally displaced in regard to the cam, and is at the same time lifted to the position *e'* so that the perpendicular *n'* to the curve occupies the position as shown in the drawing. Consequently, the point *e'* is one of the generating points of the path, to be discussed hereinafter, of said center and of all points of the grinding wheel, i. e. of a so-called relative path *R* (Fig. 5), the term "relative path" indicating that said path represents the relative motion of the grinding wheel in respect to the cam flank. As Fig. 2 shows the axis *a* of the cam *N* makes an angle of 45° with the horizontal line *H*. While the cam *N* continues its anticlockwise rotation, the grinding wheel *c* approaches the cam returning to the position in

which the two centers *d* and *e* are placed on the same level (the same horizontal line), according to Fig. 3. Thus the center *e* and the tool, i. e. the grinding wheel, have returned into the position according to Fig. 1. Then follows the machining (grinding) of the semi-circular limiting arc of the cam *N* during which period the center of the tool (grinding wheel) remains stationary, whilst the cam executes a rotation through further 180° out of its position according to Fig. 3. This position of the cam is equiva-

lent to that of Fig. 3 but as seen in a mirror; consequently the semi-circular arc of limitation is not located as in Fig. 3, but on top. From this position onwards the operation constitutes by way of the optionally selected Fig. 4, i. e. the tool (the grinding wheel) has moved downwards entraining the perpendicular to the curve n' which passes through the contact point on the cam circumference and the center e of the grinding wheel. Finally, both the tool and the workpiece return to their initial position according to Fig. 1, whence the cycle of operations begins again.

It results from the above that the workpiece, i. e. the cam to be ground, should have a constant angular velocity, and that the grinding wheel center must occupy, at any moment, a position on the perpendicular to the curve corresponding to the respective position of the workpiece. Thus the grinding is always executed in the perpendicular to the curve.

In conformity with a suggestion made, but not yet disclosed, the organ corresponding to said movement is decomposed into a first master-cam, taking care of the horizontal component of the motion, and a second master-cam to which the vertical component of the motion is assigned. Both cams are suitably keyed to the same axle in such a manner as to execute the control motion in predetermined and unalterable positions in respect to one another. The master-cams are designed in conformity with the cams on the cam shafts or the other non-circular profiles envisaged, so as to operatively warrant the production of the correct profile, regardless of the size and the wear of the grinding wheel.

A further suggestion, likewise not yet disclosed, provides for a special gear, intended to transmit the motion of the master-cam pair on to the grinding wheel by lodging the grinding wheel together with its drive in a casing block and by imparting to same, and consequently also to the grinding wheel and the motor, a swinging or oscillating motion. As the said parts, as well as the gear necessary for the drive, are of a considerable weight, there ensues the disadvantage of the weight of the moving masses unduly limiting the oscillating frequency of the grinding assembly and consequently also the efficiency of the entire machine-tool. This oscillating frequency is limited. Moreover, the weight of the oscillating masses renders necessary a most rugged construction of the machine-tool, far exceeding the conventional sizes. Finally, the nature of the drive bears upon the shape of the master-cams so that the number of the shapes of the cams, or in general of the non-circular profiles which can be produced on such machines is restricted. These considerations have given rise to the new design of a cam grinder according to the present invention which, as will be seen from the following, solves the problem in the simplest manner possible.

The essential feature of the process consists in that the workpiece rotating with a constant angular velocity, as described above, is continually subject to be ground in the perpendicular to the curve.

The essential feature in realizing this process consists in that a purely mechanical gear is used for operatively keeping the tool in the perpendicular to the curve.

According to a special embodiment of the invention, complying with the above features, two master or standard cams are provided which bear upon the tool exclusively by way of simple

feelers or contacting arms so as to compel said tool to always occupy a position in the perpendicular to the curve while acting on the work-piece.

5 In the course of the further development of the invention it has been found indispensable to insert, between the two master-cams and the tool, a link motion combining the horizontal and the vertical master-cam control movements into 10 a resultant, and transmitting same to the tool. The link motion consists of two links cinematically interlocking. According to a special embodiment of the subject matter of the invention the one contactor arm for the vertical component 15 of the movement consists of a roll-carrying feeler which is by weight continually forced to rest on the master-cam for the vertical tool motion, and which forms a portion of a one-armed lever or the projection of such an arm, carrying on its 20 free end a pendulum lever with the tool. A further feature of the invention consists in that the second contactor arm is constituted by the free end of the pendulum lever itself, said free end having the shape of a roll, and resting, in the 25 manner of a feeler, on the flank of a control slide e. g. under the action of a spring, said slide being solely displaced in the horizontal direction by the master-cam controlling the horizontal component of the total motion.

30 A further feature of the invention renders it possible to exclude the motor from the moving masses and to exclude at the same time also all accessory parts, such as the casing, a special oscillating frame, etc., from participating in the 35 swinging or oscillating motion. A further feature of the invention provides the drive of the tool i. e. of the grinding wheel being effected by way of the one-armed lever and of the pendulum lever, the driving motor being located so that its axis 40 coincides with the center of the fixed link of the one-armed lever, the driving force being thus transmitted from the motor pulley to a pulley arranged at the point of linkage of the pendulum lever and the one-armed lever, and thence by a 45 belt drive to the pulley coaxial to the tool i. e. the grinding wheel.

Owing to the suppression of the superfluous moving masses according to the above the design of the machine-tool can be considerably simplified, but additionally there ensues the advantage that for grinding a cam shaft a plurality of units, as described in the following, can be arranged on the same machine-tool, capable of operating individually, or in pairs on the same or on opposite 50 sides of the cam shaft. This eliminates the danger of breakages due to critical oscillating frequencies or interference phenomena. By this arrangement of simultaneous operation the working time is considerably reduced, and the working precision is greatly enhanced, which is a feature of particular importance in modern 55 motor and engine construction.

As appears from Fig. 6 two master-cams 1 and 2 are arranged on a shaft having the axis M, the master-cam 1 serving to produce the horizontal component of the motion of the tool i. e. of the grinding wheel 3, whereas the other master-cam 2 is used for taking care of the vertical component of the motion. A one-armed lever 5 is supported by a fixed link 4 which by these articulations is prevented from executing other motions than vertical ones. The free end of said one-armed lever 5 carries at 6 a pendulum lever 7 to the free bottom end of which i. e. at 8 the tool, 70 viz. the grinding wheel 3 is fastened.

The lever 5 is provided with a projection 10, carrying a small roll 11 which by the weight of the device is continually pressed on the circumference of the master-cam 2 so as to move, feeler-like, in unison with the eccentricities of the contours of the master-cam 2, thus transmitting its motion to the lever 5, and consequently to the pendulum lever 1.

As regards the second master-cam 1 its contour is made to control the arm 12 of the slide 13, the second arm 14 of which reaches into the range of a roll 15 so as to have said roll 15 continually contact the said arm 14. This permanent pressure of the roll to the arm is attained by a spring 16, connecting the projection 17 of the pendulum 7 with a fixed point 18. Numeral 19 refers to the workpiece to be ground by means of the wheel 3.

As already mentioned the driving organ, or more correctly, the driving system is excluded from the swinging or oscillating system by the motor 20 being located at point 4 (fixed link) and thence driving a pulley 21 which transmits the force of the motor by way of a belt to a pulley 22 located at point 6 (point of linkage), whence the force is further transmitted by a belt drive to the pulley 23 at the bearing 8. The slide 13 is made to travel in the guide 24 of the machine-bed 25.

By realizing the above principles a very simple and light-weight machine-tool is obtained as illustrated in the Figs. 7, 8 and 9. The device described above is lodged in the fixed casing 30, the levers 31 and 32 serving for starting and stopping the grinding wheel drive and for changing the speed, whereas the workpiece, i. e. the cam shaft 33 with the cams 34 is taken up between the headstock 35 and the tailstock 35^a. The hand wheels 36 and 37 are used for moving the workpiece chucks or fixing devices to or from the tool, or for displacing it in parallel thereto. The headstock 35 serves at the same time as housing for the synchronous drive for the cam-shaft motion, whilst the drive of the master-cams 1 and 2 is effected by a synchronous motor in dependence on the rotation of the workpiece.

The adjustment of the master-cams 1 and 2 is carried out by operating the hand wheel 39.

Fig. 10 is a plan showing a multi-tool arrangement provided with simplified controls.

Stress is laid on the fact that the device according to the invention permits, first of all, the construction of a unit composed of the tool and its bearing, of the feelers or contacting levers, of the master-cams, and of the drive for the tool and for the master-cams. Taking a step further these units can be built into machine-tools, as described, whereby single units or a plurality of units may be provided, the latter acting either side by side or opposite to each other.

Numeral 40 refers to the foundation frame or base plate of the machine-tool on which the known headstock 41 and the tailstock 42 are so located as to be displaceable thereon. Between the centers the workpiece i. e. the camshaft, carrying twelve cams, is set, said cams being machined simultaneously by means of e. g. four units 44, 45 and 46, 47, said units being fixed in pairs on projections 48 and 49, and being displaceable to a certain distance in the longitudinal direction of the machine tool.

For one pair of these units on each side i. e. 44, 45 and 46, 47 a hand wheel 50 is provided, used for the displacement of the master-cam shaft on the one hand, and on the other hand

for the adjustment of the master-cams to be used for the work at hand. Besides for each unit a lever 52 for starting and stopping the grinding device, and a lever 53 for changing the speed are provided.

Finally there are hand wheels 54, one on each side of the machine-tool table, for moving the units in pairs towards or from the workpiece, and another hand wheel 55 for displacing the two pairs of units in parallel to the axis of the workpiece. Furthermore, a hand wheel 56 is provided for longitudinally displacing the table on which the workpiece is fixed.

By means of the machine described which—by the way—may also be fitted with one-pair units, all cams of a four-cam shaft can be ground at once whereas an eight-cam shaft would require two successive operations, and a twelve-cam shaft three operations.

As already mentioned above the invention is not restricted to the production of cams or cam-shafts. If the two master-cams which are required for the horizontal and the vertical motion of the grinding wheel are so designed that the workpiece—rotating at a constant angular velocity—is always machined in the perpendicular to the curve, then it is always possible to produce on the same machine-tool all kinds of non-circular bodies such as triangular profiles as known. The shape and size of the masters will, of course, have to be altered according to the profiles to be ground. In case of the triangular profiles eccentricities are employed of which the one controls the horizontal motion of the tool, whilst the other having e. g. an eccentricity three-times as great as the former, takes care of the vertical motion. According to the principle on which this invention is based polygonal profiles of any number of corners can be produced.

Without departing from the scope of the invention the technical equivalents of the different details described and illustrated should be considered as being protected by this invention.

What I claim is:

1. Machine for the production of cams comprising in combination a fixed holder for the workpiece, a movable holder for rotatably carrying the tool, two rotary master-cams, means inserted between said cams and the said tool holder for moving same horizontally under the action of the one cam, and vertically under the action of the other cam, the means for horizontally moving the tool consisting in a channel-shaped stirrup displaceable under the action of the one master-cam, and the means for vertically displacing the tool consisting of a one-armed lever resting by means of a contacting organ on or against the other master-cam, and keeping the tool swingingly suspended from its free end, driving means for the tool, and driving means for the master-cams.

2. Machine for the production of cams comprising in combination a fixed holder for the workpiece, a movable holder for rotatably carrying the tool, two rotary master-cams, means inserted between said cams and the said tool holder for moving same horizontally under the action of the one cam, and vertically under the action of the other cam, the means for horizontally moving the tool consisting in a channel-shaped stirrup displaceable under the action of the one master-cam, and the means for vertically displacing the tool consisting of a one-armed lever resting by means of a contacting organ on or

against the other master-cam, and keeping the tool swingingly suspended from its free end, a pendulum lever being linked to the free end of the one-armed lever, resting under its own weight on the one master-cam by way of a contacting organ, the face bottom end of the pendulum lever carrying the tool whereas its free top end is acted upon by a tension spring so as continually to press a roll, coaxial to the tool, against the one arm of the channel-shaped stirrup for the purpose of keeping it in contact with the other master-cam, driving means for the tool, and driving means for the master-cams.

3. Machine for the production of cams comprising in combination a fixed holder for the workpiece, a movable holder for rotatably carrying the tool, two rotary master-cams, means inserted between said cams and the said tool holder for moving same horizontally under the action of the one cam, and vertically under the action of the other cam, the means for horizontally moving the tool consisting in a channel-shaped stirrup displaceable under the action of the one master-cam, and the means for vertically displacing the tool consisting of a one-armed lever, resting under its own weight on said one master-cam by means of a contacting organ consisting of a roll, running on the circumference of the master-cam, a pendulum lever being linked to the free end of the one-armed lever, the free bottom end of the pendulum lever carrying the tool, whereas its free top end is acted upon by a tension spring so as continually to press a roll coaxial to the tool against the one arm of the channel-shaped stirrup for the purpose of keeping it in contact with the other master-cam, driving means for the tool, and driving means for the master-cams.

4. Machine for the production of cams comprising in combination a fixed holder for the workpiece, a movable holder rotatably carrying the tool, two rotary master-cams, means inserted between said cams and the said tool holder for moving same horizontally under the action of the one cam and vertically under the action of the other cam, the means for moving the tool in the horizontal direction consisting of a channel-shaped stirrup displaceable under the action of the one master-cam, whereas the means for moving the tool in the vertical direction consist in a one-armed lever resting by way of a contacting organ on the other cam, said contacting organ being provided with a roll, running on the circumference of the second rotary master-cam, a pendulum lever carrying the tool, being linked to the free end of the one-armed lever, and being acted upon by a spring so as to press a roll, coaxial with the tool, on a shank of the channel-shaped stirrup, the tool being driven by a double belt drive from a motor, the axis of which coincides with the fixed link of the one-armed lever, the belt passing from the motor pulley to a guide pulley, coaxial with the axis of linkage of the pendulum lever and thence to the tool driving pulley, the means for driving the master-cams consisting of a motor and a power transmission gear for the cams.

5. Machine for the production of cams comprising in combination a fixed holder for the workpiece, a movable holder rotatably carrying the tool, two rotary master-cams, means inserted between said cams and the said tool holder for moving same horizontally under the action of the one cam and vertically under the

action of the other cam, the means for moving the tool in the horizontal direction consisting of a channel-shaped stirrup displaceable under the action of the one master-cam, whereas the means for moving the tool in the vertical direction consist in a one-armed lever resting by way of a contacting organ on the other cam, said contacting organ being provided with a roll, running on the circumference of the second rotary master-cam, a pendulum lever carrying the tool, being linked to the free end of the one-armed lever, and being acted upon by a spring so as to press a roll, coaxial with the tool, on a shank of the channel-shaped stirrup, the tool being driven by a double belt drive from a motor, the axis of which coincides with the fixed link of the one-armed lever, the belt passing from the motor pulley to a guide pulley, coaxial with the axis of linkage of the pendulum lever and thence to the tool driving pulley, the means for driving the master-cams consisting of a motor and a power transmission gear for the cams, all these parts including the driving motors for the master-cams and the tool constituting a unit, one such unit or a plurality of such units being set on one or on the two sides of a grinding machine for the purpose of grinding at the same time several cams on one cam shaft.

30 6. Machine for grinding cams, particularly cams on cam shafts, comprising, in combination, a work holder, a first lever, a pivot swingably supporting said first lever, a second lever swingably supported by said first lever, a tool shaft 35 rotatably supported by said second lever, a horizontal slide having two vertical guide surfaces, a first master cam engaging one of said guide surfaces for effecting horizontal movement of said slide to and from the work, and a second 40 master cam engaging said first lever and oscillating it on said pivot, a roller mounted on said tool shaft and engaging the other guide surface for assuring vertical up-and-down movement of said shaft upon oscillation of said first lever.

45 7. Machine for grinding cams as defined in claim 6, comprising resilient means connected with said second lever and a stationary part of said machine for affording engagement of said first lever and said second master cam and of 50 said roller and said other vertical guide surface.

3. Machine as defined in claim 6, comprising a motor for driving the grinding disc, the rotation axis of said motor coinciding with the rotation axis of said pivot, a pulley supported by 55 said levers and having an axis of rotation coinciding with the axis on which said second lever swings on the first lever, and drive means connecting said motor and said pulley and said pulley and said shaft.
